UNITED STATES PATENT OFFICE.

PATRICK JOHN WHELAN, OF DOUGLAS, ONTARIO, CANADA.

CORK EXTRACTOR AND FASTENER.

1,112,875.

Specification of Letters Patent.

Patented Oct. 6, 1914.

Application filed October 31, 1913. Serial No. 798,576.

To all whom it may concern:

Be it known that I, PATRICK JOHN WHELAN, a subject of the King of Great Britain, and resident of the town of Douglas, in the 5 Province of Ontario, Dominion of Canada, have invented certain new and useful Improvements in Cork Extractors and Fasteners, of which the following is the specification.

10 My invention relates to cork extractors and fasteners, and the objects of my invention are to extract the cork and secure the same in position when replaced in the bottle, and it consists essentially of a corkscrew 15 having an orifice in the top end, a cross bar or gripping means pivotally engaging with such orifice and designed to engage with the neck of the bottle, a slot in such spring member and a ring engaging with the said slot, 20 the parts being arranged and constructed in detail as hereinafter more particularly explained by the following specification.

Figure 1 is a perspective view of my device as attached to a cork and bottle. Fig. 2 is a perspective view showing my device being attached to or detached from the neck of the bottle. Fig. 3 is an enlarged perspective view of my device. Fig. 4 is a perspective view of my device in the final position when extracting a cork. Fig. 5 is a perspective view of an improved device. Fig. 6 is a part section taken through the cross bar or gripping member of Fig. 5.

Like letters of reference refer to like parts 35 in the several drawings.

Referring to the drawings, A represents a neck of a bottle with a cork 1 engaging therein. A corkscrew 3 is fixed in the cork in the usual way, the top end of such cork-screw being bent in a loop 5 forming an orifice 4 therein. The cross bar or gripping member 2 of the fastener 8 extends transversely across the corkscrew and is suitably reduced at the center to engage with and free 40 to turn in the orifice 4, the sides of the loop 5 engaging with the shoulders 6 and 7 so formed on the bar 2. The ends 9 of the fastener 8 are bent substantially at right angles to the bar 2 and their extreme ends 45 are splayed out at the foot to form the ends 10 designed to engage with the neck A of the bottle. The slot 11 extends on one side of the

bar 2 and terminates at the head 5 of the corkscrew 3 and has a ring 12 loosely engaging with it, the ring 12 being designed to be 55 attached to the bar 2 by means of the clip fastener 13 formed therein.

Referring to the Figs. 4, 5 and 6 in which is shown an improved form of my device particularly adapted to suit bottles of large size, the corkscrew 3 and the end piece 5 are formed with a tongue and grooved joint and hinged together by means of the rivet 14, the corkscrew being adapted to be turned into a position to lie along the bottom face 65 of the bar 2. 16 represents an adjustable piece mounted in the groove 17 in and extending along the bottom face of the bar 2, such adjustable piece being provided with a threaded orifice 23 therethrough. 18 represents a threaded screw designed to engage with the threaded orifice 23 in the adjustable piece 16, the outer end of such screw being provided with a knob 21 while the inner end is loosely mounted in the projection 70 19 and secured in position by means of the collars 20. The ends 9 are formed with a tongue designed to fit into a groove in the adjustable piece 16 at one end and into a groove in the piece 25 at the other end of the 80 bar 2 and are pivotally secured therein by the rivets 15. 24 represents a spring secured to the bar 2 and adapted to engage with the tongue on the ends 9. It will, of course, be understood that the spring 24 may be located 85 in other positions, as for instance between the top of the tongue on the end 9 and the groove in the movable part 16.

Having described my invention I will now show the method of operation. 90

The corkscrew 3 is inserted in the cork 1 and the bar 2 turned with respect to the corkscrew 3 until the ends 9 take up a vertical position as shown in Fig. 4. The ring 12 is now held vertical, the lower end leaning 95 against the side of the loop 5 when a combined pull on the ring 12 and the bar or gripping member 2 pulls the cork. The cork is replaced and the ring 12 swung into the position shown in Fig. 2, the fastener 8 100 now being turned, the ends 10 engage with the neck A of the bottle. The ring 12 is now swung into position parallel to the top face of the cork and the clip 13 engages with

the rod 2 so preventing the ring 12 from moving or catching on anything. By this means a cork returned to a bottle can be held securely in position and since the corkscrew 5 is not removed the life of the cork is much greater than in cases where a corkscrew has to be inserted each time the cork is removed.

The principal feature of the ring 12 is to facilitate the removal of corks from large 10 bottles.

In the improved device as shown in Figs. 4, 5, and 6, the threaded screw 18 can be operated to permit of the adjustable piece 16 being moved inwardly toward the corkscrew 3 whereby the ends 9 can be adapted 15 to fit any size of bottle within a certain limit.

This device when out of commission is adapted to be folded together to carry in 20 the pocket and to facilitate this the corkscrew 3 is turned into the position coinciding with the bottom face of the bar 2 when the ends 9 are folded inwardly, such ends forming a guard to prevent the point 25 of the corkscrew from catching on the pocket lining.

The device is constructed of spring steel wire or any other suitable resilient material.

30 From this description it will be seen that I have invented an article strong, cheap of manufacture, compact and of great utility and particularly adapted to transporting of bottled goods.

35 As many changes could be made in the above construction and many apparently widely different embodiments of my invention, within the scope of the claims, constructed without departing from the 40 spirit or scope thereof, it is intended that all matter contained in the accompanying specification and drawings shall be interpreted as illustrative and not in a limiting sense.

45 What I claim as my invention is:

1. A cork extractor and fastener comprising a corkscrew and a gripping member extending transversely across the corkscrew and free to turn with respect to the 50 same, said gripping member having means to engage and grip the neck of the bottle, and means of adjusting the said neck gripping means.

55 2. A cork extractor and fastener comprising a corkscrew, a gripping member extending transversely across the corkscrew and free to turn with respect to the same, the ends of said gripping member being bent substantially at right angles 60 and splayed out to engage and grip the neck of the bottle, a slot extending through one side of the said gripping member and terminating at the corkscrew, and a ring loosely engaging with the said slot and 65 having a clip designed to engage with the

gripping member, as and for the purpose specified.

3. A cork extractor and fastener comprising means for engaging the cork consisting of a head having a groove therein, 70 a corkscrew pivotally mounted in such head, a gripping member extending transversely across the corkscrew and free to turn with respect to the same, the ends of said gripping member being bent substantially at right angles and splayed out to engage and grip the neck of the bottle, a slot extending through one side of said gripping member and terminating at the head of the said corkscrew, a ring loosely 75 80 engaging the said slot and having a clip designed to engage with the gripping member and means of turning the said ends into position to lie along the underface of the said gripping member.

4. A cork extractor and fastener comprising means for engaging the cork consisting of a head piece having a slot therein and a corkscrew pivotally mounted in such slot, a gripping member extending transversely across the cork screw and free to turn with respect to the same, one end of such gripping member being bent substantially at right angles and splayed outwardly to engage the neck of the bottle, the side 90 remote from such end having a groove in and along the bottom face, an adjustable member having a threaded orifice therethrough engaging with the said groove, the ends of such member being splayed outwardly to engage the neck of the bottle, a threaded screw engaging with the said threaded orifice and held in position by collars engaging with its inner end, the outer end being provided with a knob, a slot extending through that side of the said gripping member remote from the adjustable end, such slot terminating at the corkscrew, a ring loosely engaging with the 95 said slot and having a clip designed to engage with the gripping member, as and for the purpose specified.

5. A cork extractor and fastener comprising means for engaging the cork consisting of a head piece provided with a slot, 115 a corkscrew pivotally engaging in such head piece, a gripping member extending transversely across the corkscrew and free to turn with respect to the same, one end of such member being bent substantially at 120 right angles and having a groove therein, the other end of such gripping member being provided with a groove in and extending along its bottom face, an adjustable piece provided with a groove designed 125 to engage with the groove in the said gripping means, such adjustable piece having a threaded orifice therethrough, a threaded screw engaging with such orifice and held in position by collars engaging its inner 130

end, the outer end being provided with a knob, neck gripping means, one end of which is splayed outwardly to engage the neck of the bottle, the other end having a tongue adapted to fit the groove in the said adjustable member and the groove in the said opposite end of the said gripping member, and springs engaging with the

10 said neck gripping means, as and for the purpose specified.

In witness whereof I have hereunto set my hand in the presence of two witnesses.

PATRICK JOHN WHELAN.
